(57) **CLAIM**

The ornamental design for a rotating latch, as shown and described.

DESCRIPTION

FIG. 1 is a top, front, right perspective view of a rotating latch showing my new design;

FIG. 2 is a top, rear, right perspective view thereof;

FIG. 3 is a bottom, front, right perspective view thereof;

FIG. 4 is a bottom, rear, right perspective view thereof;

FIG. 5 is a front elevational view thereof;

FIG. 6 is rear elevational view thereof;

FIG. 7 is a top plan view thereof;

FIG. 8 is a bottom plan view thereof;

FIG. 9 is a right side elevational view thereof; and,

FIG. 10 is a left side elevational view thereof.

The broken lines illustrate environment and form no part of the claimed design.
